UNITED STATES PATENT OFFICE

110,199

DESIGN FOR AN ANTENNA FOR AUTOMOBILE RADIOS

John Raymond Stimpson, Shelby, Mont.

Application March 4, 1936, Serial No. 61,467

Term of patent 14 years

To all whom it may concern:

Be it known that I, John Raymond Stimpson, a citizen of the United States residing at Shelby, in the county of Toole and State of Montana, have invented a new, original, and ornamental Design for an Antenna for Automobile Radios, of which the following is a specification reference being had to the accompanying drawings, forming a part thereof.

Figure 1 is a side elevation of an antenna of my new design.

Figure 2 is a plan view of my antenna.

Figure 3 is a top view of one of the insulators of my antenna, shown in larger scale.

Figure 4 is a sectional view taken along the line 4—4 of Figure 2.

Fig. 5 is a perspective view of the radio antenna of my design.

The device of this design is intended to be attached to the top of an automobile body.

I claim:

The ornamental design for an antenna for automobile radios, as shown and described.

JOHN RAYMOND STIMPS.
